UNITED STATES PATENT OFFICE.

CORNELIUS A. SULLIVAN, OF BROOKLYN, NEW YORK.

BOOK-BINDING.

SPECIFICATION forming part of Letters' Patent No. 462,959, dated November 10, 1891.

Application filed May 2, 1891. Serial No. 391,320. (No model.)

To all whom it may concern:

Be it known that I, CORNELIUS A. SULLIVAN, a citizen of the United States, residing at Brooklyn, in the county of Kings and State 5 of New York, have invented an Improvement in Book-Binding, of which the following is a specification.

Before my invention albums and scrap-books had been made with a backing-piece 10 folded backward and forward like a fan, with the sheets secured at the back folds, the intervening folds serving to keep the sheets or groups of sheets apart to give space for the pictures or other articles pasted upon the 15 leaves of the scrap-book, and blank or account books had been made with filling-strips intervening between the back folds of the groups of sheets and the bound back of the book. In cases where filling-strips have been introduced 20 between the fold at the back of the sheets and the back of the book difficulty has been experienced in consequence of the glue applied to the back of the book running in between the filling-pieces and upon the sheets 25 of the book and either causing them to stick together or marring the appearance when the book is opened. All these difficulties are overcome 30 by my present improvements, which relate to the peculiarities of construction and combination of devices hereinafter set forth.

In the drawings, Figure 1 is a cross-section, and Fig. 2 a partial perspective rear view, of the folded foundation. Fig. 3 is a perspective view, partially in section, of the folded- 35 foundation filling-pieces and sheets. Fig. 4 is a cross-section in larger size of one form of filling-piece; and Fig. 5 is a section showing the manner of applying the fly-sheets and cover.

The folded foundation A is preferably of muslin, to which a thin sheet of paper is pasted, which paper may be either at the inside or the outside portion of the folded foundation, and this folded foundation is thickened 40 by strips of paper or similar material pasted upon the back surface thereof, as at 2, and such strips of paper pass across the foundation, and they are applied at places where the sewing-threads do not come in the 45 sewing, and these strips should be of sufficiently thick paper to compensate for the thickness of the sewing-threads in order that

when the backing of the book is clamped or compressed the sewing-threads may not be unduly pressed upon, and the entire backing 55 will be uniform and equally compressed.

The sheets of the book are associated together in groups or sections of two, three, or more such sheets laid together and folded at the back, as shown at B.

Across the back of the book and behind the folded foundation A there are tapes or bands 4, as usually provided in blank or account books, and the sewing-threads 3 pass from the inside of the fold of the sheets B through 65 the inner folded edge of the foundation and around the crossing tapes or bands 4, and the sewing is preferably the regular blank-book 70 sewing; but it may be of any desired character. Usually the foundation A at the back will be notched near the ends for the catch-stitches or interlooping of the sewing-threads 3, as seen at 5, and it is to be understood that the sewing-threads are to be applied at the place where the strips 2 of filling-paper do 75 not come. Hence the back will be of uniform thickness, or nearly so, from top to bottom.

When the book is opened out, the folded foundation will separate or spread apart at the extreme back and the inner and visible 80 surfaces of the folded foundation will not have been stained by the glue applied to the back in the final binding operations. Hence the appearance of the book will not in any manner be marred, and the groups or sections 85 of the leaves will fold or swing at the points of attachment between such groups or sections of leaves and the inner edges of the folded foundation. Hence the leaves of the book will open out flat, or nearly so, which is 90 a great convenience for blank and account books, and also for albums.

The folded foundation, when thickened by the strips 2 of paper, may in itself be as thick as the groups or sections of leaves to be attached to said foundation; but usually this will not be the case, and to adapt the folded foundation to the entire thickness of the book filling-strips C are to be introduced from the back, between the respective folds of the foundation, and such filling-strips may be of paper or card-board or any similar material, and usually it is advantageous to make such filling-strips two-part—that is to say, com-

- posed of two narrow strips placed edge to edge—and by wrapping these filling-strips with muslin or similar material, as shown in Fig. 4, the filling-strips will be connected together by the muslin and form a longitudinal hinge between the two parts. This will increase the flexibility of the folded foundation and allow for the book opening out more easily, and with this form of filling-strips the sewing-threads pass transversely through the filling-strips in order that such filling-strips may keep the parts in their proper relative positions and maintain the proper tension upon the sewing-threads.
- 15 In finishing up the back of the book it is advantageous to apply the liquid glue to the back of the folded foundation in such a manner that the glue will run in between the folded foundation and the filling-strips and around the threads, to a greater or less extent, and this can advantageously be done immediately before the clamping-pressure is applied at opposite sides of the back in rounding-up such back and completing the binding operation.
- 20 A convenient manner of connecting the filling-strips C to the foundation is shown in Fig. 5, where the strips C are glued or pasted to the foundation advantageously before the foundation is folded, and these strips may be single, as seen at C', or two-part, as seen at C², or folded, as seen at C³ C⁴, according to the thickness required and the convenience of the maker. Where these strips are pasted to the surface of the folded backing, the sewing-threads pass through between the double strips, and the sewing is more easily performed than where the filling-strips have to be perforated, as in Figs. 1 and 4.
- 25 The covers of heavy books are usually made of two or more thicknesses of mill-board or pasteboard and the back-bands are passed in between these boards. Upon reference to Fig. 3 it will be seen that the bands 4 come between the strips 2. Hence when the foundation material is folded double, as shown in Fig. 5, and put in between the two boards E of the cover and the parts glued firmly together, the foundation between the strips is about the same thickness as it is at the strips, and uniformity of strength is obtained. The fly-leaves G are sewed to the foundation at the back fold thereof, as usual, in book-binding, and such fly-leaves may be strengthened by strips of muslin at 7, pasted to the same at the back fold, and one or more of the fly-leaves are to be pasted to the inside of the cover.
- 30 I claim as my invention—
- 35 1. The combination, with the folded foundation, of the cross tapes or bands at the back of such folded foundation, the sheets composing the book grouped in sections, and the sewing-threads passing through the folds of

the groups of sections, through the inner edges of the folded foundation, and around the crossing tapes or bands, substantially as set forth.

2. The folded foundation of muslin or similar material thickened at places by strips of filling material fastened to the surfaces of such folded foundation, in combination with tapes, cords, or bands passing across the back, the leaves folded and associated in groups, and the sewing-threads passing through the backs of the folded groups of leaves and through the folded foundation and around the tapes, cords, or bands of the back, substantially as set forth.

3. The combination, with the sheets folded and grouped in sections, of a folded foundation for the back, having strips of paper or similar material applied to such foundation transversely and where the sewing-threads do not come, tapes, cords, or bands across the back of the book, and sewing-threads passing through the groups of leaves and the folded foundation and around the tapes, cords, or bands at the back, substantially as set forth.

4. The two parallel narrow filling-strips, in combination with the groups or sections of leaves, a folded foundation thickened at the places where the sewing-threads do not come, and inclosing the filling-strips, and sewing-threads passing through the groups of sheets and through the foundation and united at the back of the book, substantially as set forth.

5. The combination, with the folded foundation and the sheets in groups or sections, of longitudinal filling-strips within the folded foundation, and crossing tapes, bands, or cords at the back, and sewing-threads passing through the groups or sections of sheets and through the folded foundation and the filling-strips and around the crossing tapes or bands, substantially as set forth.

6. The combination, with the folded sheets in groups, of a folded foundation, filling-strips fastened to the interior of the folds of the foundation, and sewing-threads passing through the group of sheets through the folded foundation and between the filling-strips within the foundation-folds and united at the back of the book, substantially as set forth.

7. The combination, with the book-covers and the sheets in groups, of a folded back of muslin, cross-bands at the back, and sewing-threads uniting the groups of sheets to the inner edges of the folded foundation and to the cross-bands, such foundation at its edges and the ends of the bands being united to the covers, substantially as set forth.

Signed by me this 29th day of April, 1891.

C. A. SULLIVAN.
